United States Patent Office.

ELWIN E. BERRY, OF FARMINGTON, NEW HAMPSHIRE.

Letters Patent No. 78,177, dated May 26, 1868.

IMPROVED TABLE-LEAF SUPPORT.

The Schedule referred to in these Letters Patent and making part of the same.

TO ALL PERSONS TO WHOM THESE PRESENTS MAY COME:

Be it known that I, ELWIN E. BERRY, of Farmington, in the county of Strafford, and State of New Hampshire, have invented an Improved Table-Leaf Supporter; and I do hereby declare the same to be fully described in the following specification, and represented in the accompanying drawings, of which—

Figure 1 is a front elevation, and

Figure 2, a transverse section of a table provided with my invention, which is an improved means or mechanism for supporting a leaf of the table when such leaf is in a horizontal position, such mechanism readily admitting of the table-leaf being dropped or turned on its hinges into a vertical position or plane.

In the drawings, A denotes a common table, having two leaves, *a a*, so hinged to opposite edges of its top, *b*, as to render each leaf capable of being turned from a horizontal down into a vertical position, or from the latter to the former, as circumstances may require.

The hinges of one of the leaves, or that which is represented in the drawings as elevated into a horizontal position, are shown at *c c*.

In carrying out my invention, I hinge or connect to the leaf a curved arm or strut, B, and extend it through a staple or yoke, *c*, fixed to the lower edge of the next adjacent bar, *d*, of the leg-frame of the table, such staple or yoke being formed as represented in the drawings.

The arm or strut B is chambered lengthwise to receive a gravitating-lever or catch, D, formed as shown in figs. 1 and 2. This latch turns on a pin, *e*, going through it and the arm or strut, and being arranged therein in manner as represented in fig. 2.

When in its lowest position the lever-catch D projects below the strut a short distance, and is supported by resting against the end of the chamber in the strut.

On elevating the table-leaf to a horizontal position, the gravitating-catch D will drop down, and, by bearing against the front edge of the yoke or staple C, will, in conjunction with the curved arm, support the leaf in such position.

When the catch D is in its lowest position, its shorter arm, *f*, will extend above the upper edge of the arm B, so as to enable a person, by grasping the arm and the part so extended, to readily move the catch, so as to throw it out of engagement with the staple or yoke before proceeding to depress the table-leaf.

The advantage of the curved arm or strut and gravitating-catch over a curved arm only having one or more notches or teeth to act against the yoke, is, that such an arm as last mentioned is very liable to be accidentally thrown out of engagement with the staple, particularly after the two may have become more or less worn. This may be occasioned by a person while leaning against the table-leaf, or while sitting at the table.

With my invention, or combination of gravitating-arm or catch with the curved arm, the danger of accidental disengagement of the table-leaf supporter with the staple or yoke is very much lessened, if not rendered impossible.

I would remark that, if desirable, a spring may be applied to the curved arm and its catch, so as to press the latter downward within the arm.

What, therefore, I claim as my invention, is—

The combination of the lever-catch D, or its mechanical equivalent, with the arm or strut B, and the staple C, so as to operate therewith, as described, when they are applied to a table or other like article, substantially in manner as specified.

ELWIN E. BERRY.
